UNITED STATES PATENT OFFICE.

THOMAS BREAKELL, OF WIRKSWORTH, NEAR DERBY, ENGLAND.

GRINDING AND PULVERIZING MILL.

SPECIFICATION forming part of Letters Patent No. 733,574, dated July 14, 1903.

Application filed February 13, 1902. Serial No. 93,943. (No model.)

To all whom it may concern:

Be it known that I, THOMAS BREAKELL, mechanical engineer, a subject of the King of Great Britain and Ireland, residing at Brasington Hall, Wirksworth, near Derby, in the county of Derby, England, have invented an Improved Grinding and Pulverizing Mill, (for which I have made application for Letters Patent in Great Britain, No. 18,637, and dated the 18th of September, 1901,) of which the following is a specification.

This invention relates to grinding and pulverizing mills in which the material dealt with is ground between dies on a rotating part and dies on a fixed part.

My invention consists in certain devices and combinations, which will be described in the specification and pointed out in the claim.

Referring now to the accompanying drawings, which illustrate my invention, Figure 1 is a front elevation of a grinding or pulverizing mill with the front of the casing removed. Fig. 2 is a side elevation, partly in section, of the same. Fig. 3 is a front elevation of the same, showing the screen through which the material leaves the mill. Figs. 4 and 5 show the moving and fixed dies.

1 is a casing held down on a suitable foundation by bolts 2. To the inside periphery 30 of the casing are fixed the blocks or dies of steel 8 by means of the taper-headed bolts 9. The nuts on the bolts 9 may be run out and wood or other packing placed between the dies 8 and the casing 1 as the dies 8 are worn away through the working of the mill.

35 7 is a shaft which is revolved by any suitable means.

4 is a disk, preferably of cast-iron, which is fastened onto the end of the shaft 7 and revolves with it inside the casing 1. To this disk are attached the dies or shoes of steel 5 by means of the taper-headed bolts 6. The nuts on these bolts may also be run out and packing placed between the shoes and the rim 45 of the disk 4. In this way the shoes 5 and the dies 8 may be arranged to work at a greater or a less distance from each other; but in actual work I do not allow them to touch. The sides of the casing 1 are when necessary

protected from wear by means of the lining- 50 plates 11.

10 is a hopper into which the material to be ground is fed.

12 is a water-tight stuffing-box.

13 is a pipe for feeding clean water or air 55 into an annular space 17, surrounding the shaft 7, in order to prevent grit from passing between the casing 1 and the shaft 7, and thereby damaging the shaft or casing.

14 is a frame attached to the casing 1 by 60 bolts 15, and 16 is a screen attached to the frame 14 by the bolts 18.

The material to be ground is fed into the hopper 10, (water in the case of wet-grinding having been first turned on at the pipe 13.) 65 The material falls directly between the revolving shoes and the fixed dies 8, with the result that it is hammered and ground. When fine enough to pass the screen 16, the water passing through carries the material with it. 70 When grinding dry material, a current of air may be passed through the pipe 13 and the fine material would then be taken through the screen by the air, or the dry material may be removed by a current of air without any 75 screen, as is at present done with other pulverizers, and settled in a chamber. My invention relates to the grinding portion of the apparatus and not to the screening of the material being ground.

80 The fixed dies and the moving shoes are shown in section and plan in Figs. 4 and 5, respectively. Both the dies and shoes may be formed of solid blocks of metal or any other suitable material, preferably hard steel, 85 with one hole through the center for the taper-headed bolts 9 and 6, by which they are fixed to the casing 1 and disk 4, or they may be formed with a number of holes through them, as shown in Figs. 4 and 5, to give them a better grip on the material being treated, or they may be made with a number of ribs or corrugations on their wearing-surfaces, as may be desired, to treat any particular substance.

Having now described my invention, what 95 I claim as new, and desire to secure by Letters Patent, is—

In combination, the cylindrical casing,

grinding-shoes of gradually-increasing thickness fixed to the inner periphery of said casing and arranged with relatively small spaces between adjacent shoes, a shaft adapted to rotate 5 in said casing, a disk carried by said shaft, grinding-shoes fixed to said disk with relatively small spaces between adjacent shoes, a frame secured to one side of said casing and a screen carried by said frame and inclined

to the plane of said disk and perpendicular to a vertical plane containing said shaft, substantially as described.

In witness whereof I have hereunto set my hand in presence of two witnesses.

THOMAS BREAKELL.
